ADJUSTABLE DELAY LINE

John H. Rubel, Albany, and Roy E. Troell, Schenectady, N. Y., assignors to General Electric Company, a corporation of New York

Application August 12, 1943, Serial No. 498,380

2 Claims. (Cl. 178—44)

1

Our invention relates to high frequency signalling systems and it has for its object to provide an improved delay circuit for use in the transmission of such signals.

In pulse signalling systems of the type in which a received signal pulse is transmitted to a cathode ray oscilloscope to produce a vertical or radial deflection of the cathode ray beam therein and which employ a sweep circuit to produce a horizontal or angular deflection of the beam, it is desirable to employ means to delay transmission of the received pulse to the proper electrodes of the oscilloscope until operation of the sweep circuit is initiated. Accordingly, it is an object of our invention to provide an improved circuit for delaying the transmission of a pulse by a determinable period of time.

It is another object of our invention to provide a new and improved continuously adjustable delay device for a high frequency signalling system.

It is a further object of our invention to provide a new and improved artificial transmission line of compact form and simple construction.

It is still another object of our invention to provide a new and improved delay circuit for a pulse signalling system in which relatively long delays may be obtained with very little distortion of the pulse signal.

The features of our invention which we believe to be novel are set forth with particularity in the appended claims. Our invention itself, however, both as to its organization and method of operation; together with further objects and advantages thereof, may best be understood by reference to the following description taken in connection with the accompanying drawing, in which Fig. 1 diagrammatically illustrates an artificial transmission line constructed in accordance with our invention and Fig. 2 is an end view of the artificial transmission line of Fig. 1. Fig. 3 illustrates diagrammatically a continuously adjustable delay device for a high frequency signalling system. Fig. 4 is a modification of the artificial transmission line of Fig. 1 and Fig. 5 is another modification of the artificial transmission line of our invention.

Referring now to Figs. 1 and 2, jointly, we have shown there an artificial transmission line 10 comprising an insulated conductor 11 formed into a helical coil of closely wound turns and surrounding a core of small insulated conductors 12. A layer of insulation 13 is wrapped around the conductors 12 to form them into a compact core, and the helical coil 11 is wound upon this core. A layer of insulation 14 of any suitable material 55

2

may be wound about the helically coiled conductor 11.

The conductor 11 preferably is of solid copper wire covered with a suitable insulating material 15, such as a varnish of organic material. The insulated conductors 12 preferably are formed of litz wire, i. e., a wire composed of fine copper strands, each insulated, and braided together. The strands of the core are soldered together at 20 one end 16 to form an electromagnetic ground which functions as the inner conductor of the transmission line 10, the outer conductor being formed by the solenoid or helically coiled conductor 11. When constructed in the manner outlined, the line 10 has a large distributed capacitance between the electromagnetic ground constituted by the core 12 and the helically coiled conductor 11. The transmission line likewise has distributed inductance which consists of the inductance of the coiled conductor 11. Such an artificial transmission line has a relatively low velocity of propagation for currents thereon and functions to produce a determinable delay in the transmission of high frequency currents therethrough.

Referring to Fig. 3, we have there shown a device for producing a continuously adjustable delay in the transmission of high frequency signals. This device comprises a transmission line 30 10 constructed as outlined in the discussion of Fig. 1 and comprising the helically coiled conductor 11 and the core of litz wires 12 soldered together at the ends 16 and grounded at these points. This transmission line may be connected across any suitable source of high frequency signals, such as the source 18. The transmission line 10 is formed as a portion of a circle and the source 18 is connected between one terminal of the coiled conductor 11 and ground. 35 The opposite terminal of conductor 11 is connected to ground through an impedance 23, whose value is equal to the characteristic impedance Z_0 of line 10. Individual turns of the conductor 11 are insulated from each other and 40 each turn has an uninsulated portion 19 which is contacted by a movable contact arm 20. Any suitable output circuit 21 may be connected between the movable contact 20 and ground. 45

In a pulse signalling system, the source 18 may 50 comprise a received signal pulse and the output circuit 21 may comprise the electrodes of a cathode ray oscilloscope for producing vertical or radial deflections of the cathode ray beam in the oscilloscope. In such a circuit, by adjustment 55 of the contact arm 20, a continuously variable

delay in the transmission of a received signal pulse from the source 18 to the output circuit may be obtained. Such an arrangement is particularly desirable in signalling systems in which a variable time delay in the transmission of received signals is desired so that the leading edge of the signal appears on the oscilloscope picture when the operation of the sweep circuit has been initiated by the received signal.

In the modification of our invention shown in Fig. 4, the helically coiled conductor 11 wound about the core of litz wires 12 is surrounded by a braided litz wire 38 which is opened to a desired diameter and slipped over the coiled conductor 11 or is braided directly over conductor 11. In a transmission line constructed as shown in Fig. 4, the distributed capacitance of the line is increased due to the presence of both the core 12 and the braid 38. In this form of our invention, the strands of the braid 38 and the strands of the braid 12 preferably are soldered together at one or both ends to form an electromagnetic ground for the transmission line.

In Fig. 5, we have shown still another modification of our invention in which the core of litz wires used in the previously described embodiments is not employed and the insulated conductor 11 is wound as a helical coil of closely wound turns on a substantially cylindrical form 35 of dielectric material and, in turn, is surrounded by a litz wire braid 30. The insulating form 35 preferably is sufficiently rigid to permit accurate winding of the coil 11, yet flexible enough that it can be coiled on a small radius after it has been wound and may be constituted by any suitable dielectric material, for example, molded polyvinylidene chloride. The braided litz wire 30 in this embodiment of the invention is soldered together at one or both ends, or at any desired intermediate point, to function as an electromagnetic ground for the transmission line.

A typical artificial transmission line, constructed as shown in Fig. 5, was formed by a 2.8 mil wire covered with an organic enamel so that its over-all diameter was 3 mils and was wound on a polyvinylidene chloride core having a diameter of $\frac{1}{16}$ inch. The solenoid was covered by a single layer of litz braid. Such a delay line, formed of 130 turns of the conductor 11 per centimeter of length, was found to have an inductance per centimeter of 30 microhenries and a capacitance per centimeter of 31 micromicrofarads. This line had a characteristic impedance of 1200 ohms and produced a delay of one microsecond per 33 centimeters length of the line, the attenuation being only one decibel per microsecond delay. Such a line was found to be particularly suitable for high frequency applications and, when transmitting a one microsecond square wave pulse, produced no significant distortion of the pulse shape.

While we have shown a particular embodiment of our invention, it will of course be understood that we do not wish to be limited thereto since various modifications may be made, and we contemplate by the appended claims to cover any such modifications as fall within the true spirit and scope of our invention.

What we claim as new and desire to secure by Letters Patent of the United States, is:

- 10 1. A device for producing a continuously adjustable delay in the transmission of a high frequency signal from a source of signals to an output circuit comprising, a conductor formed into a helical coil of closely wound turns, said turns being insulated from each other, a core of small strands of insulated conductors, said conductors being braided together throughout the length of said core and conductively connected at one end thereof, said source of signals being connected between one end of said coil and said core, said coil having a movable contact, and said output circuit being connected between movable contact and said core.
- 15 2. In a signalling system of the type having a source of high frequency signal and an output circuit, means for delaying the transmission of a signal between the source and the output circuit by an adjustable amount, said means comprising a helical coil of closely wound and insulated turns of a conductor, a core of small insulated wires longitudinally disposed within said coil throughout the length thereof to form therewith a section of transmission line having a low velocity of propagation for signal currents 30 thereon, said wires being braided together throughout the length of said core and being conductively connected at one end thereof, said source being connected between said coil and said core, and means connecting said output 35 circuit to a variable point on said coil.
